(57) **CLAIM**

I claim the ornamental design for a boat fender hook, as shown and described.

DESCRIPTION

FIG. 1 is a perspective view of the boat fender hook showing my new design;

FIG. 2 is a left side view thereof;

FIG. 3 is a top view thereof;

FIG. 4 is a bottom view thereof;

FIG. 5 is a rear elevational view thereof; and,

FIG. 6 is a front elevational view thereof.
